PHILIP MASON CABELL, OF NEW YORK, N. Y.

APPARATUS FOR GASIFYING LIQUID FUEL

Application filed July 17, 1923, Serial No. 652,011. Renewed February 19, 1931.

This invention relates to apparatus for converting liquid fuel into fixed combustible gas.

In apparatus made in accordance with the invention a liquid fuel, such as kerosene, gas oil, fuel oil, or other heavy oil, or other relatively non-volatile liquid fuel, is converted into fixed combustible gas by vaporizing it and heating it in the presence of steam to a temperature sufficient to crack the oil and to dissociate the steam. This operation takes place in a converter which is maintained at the required temperature by partial combustion of the fuel therein. A suction device is used to draw gas from the converter and to maintain a sub-atmospheric pressure in the converter which is utilized to draw fuel into the converter and to draw air into the converter to support partial combustion therein. Steam is supplied to the converter. A feature of the invention consists in limiting the combustion to a desired part of the converter and in extending the zone of combustion, by introducing steam into the converter at a rate which may be regulated.

Other features and advantages of the invention are hereinafter set forth in connection with a detailed description of practical apparatus embodying the invention. Such apparatus may be used as part of a complete apparatus for producing mechanical power from liquid fuel and is so shown in the accompanying drawings, in which:

Fig. 1 is a diagrammatic side elevation of the complete apparatus;

Fig. 2 is a vertical section of the converter sectioned on the line 2—2 of Fig. 8;

Fig. 3 is an enlarged vertical section of the upper part of the converter, with parts removed, taken on the line 2—2 of Fig. 8, and showing the oil and air inlets;

Fig. 4 is a similar view showing the valve through which the steam is admitted to the converter;

Fig. 5 is a partial vertical section of the converter, taken on the line 5—5 of Fig. 8, and showing the pyrometer and the gas outlet from the converter;

Fig. 6 is a top view of the converter, omitting the steam supply pipe and needle valve;

Fig. 7 is a fragmentary horizontal section on the line 7—7 of Fig. 3, showing the air inlet;

Fig. 8 is a horizontal section of the converter on the line 8—8 of Figs. 2 and 5; and

Fig. 9 is a side elevation of the cut-off valve between the starting lamp and the converter.

The general arrangement of the apparatus is shown in Fig. 1. The system as shown includes an internal combustion engine, indicated diagrammatically at E, and a converter C. The engine may be of any ordinary gas or gasoline type. The intake manifold E1 of the engine is connected by piping 10 to the gas outlet of the converter C. The suction of the engine produces a partial vacuum in the converter C which draws air into the converter through a pipe 13. The outer end of this air supply pipe communicates with a heater 14 which surrounds a portion of the exhaust pipe E2 of the engine. The liquid fuel is fed by gravity from a tank 15 to a float chamber 16 through a fuel supply pipe 17. From the float chamber 16 the fuel is drawn into the converter by the partial vacuum in the converter aided and modified by air flow through the Venturi inlet herein-after described.

The supply of oil in the tank 15 may be maintained by pumping oil into the tank 80 from a storage tank (not shown in the drawings) by means of a pump 20 driven by the engine E. An overflow pipe 21 leads from the upper part of the tank 15 to the storage tank.

Waste heat is utilized to furnish steam to the converter. Such waste heat may be taken from the exhaust gases of the engine. In order to utilize it, a flash boiler B, formed of a coil of pipe, is placed in a casing 23 through which the exhaust gases from the engine E pass after they leave the heater 14. Water is supplied to the flash boiler from a water tank 24 through a pipe 25. The steam formed in the flash boiler B passes through a pipe 26 to an expansion chamber 27 and thence through a pipe 28 into the converter C. A part of the steam may be passed through a pipe 29 branching from the pipe 28 into a heater 30 surrounding part of the fuel

pipe 17. The pipe 29 contains a valve 31 which need be opened only in case the fuel used is so heavy or viscid that it is desirable to heat it to make it more fluid.

5 The apparatus illustrated in Fig. 1 thus forms a complete system for converting liquid fuel into a fixed gas and utilizing this fuel to produce mechanical power. The method and apparatus for producing mechanical power herein illustrated and described are not claimed in this application. So far as the present invention is concerned the internal combustion engine operates merely as a suction device serving to draw 10 gas from the converter at the rate at which it is desired to use the gas.

15 The converter, or gas generator, C, which of itself embodies important features of the invention, has in the apparatus shown the form of a vertical cylinder. It has an outer insulated wall, or casing, C1 and an insulated bottom C2. Within the wall C1 and spaced therefrom is an inner casing, or cylindrical pot, C3 which is open at the bottom 20 and has a metal cylindrical wall C4 protected by inner and outer facings C5, C6, of refractory material. The pot C3 is suspended in the converter by an outwardly extending flange C7 formed at the top of the cylindrical wall C4 of the pot and resting in a recess at the top inner edge of the outer 25 wall C1.

30 In the pot C3 are a series of horizontal foraminous trays or screens C10, C12, C13. On these trays are permeable and absorbent beds or layers C14, C16, C17, of refractory material. The beds are most desirably formed of small pieces of porous and absorbent refractory material, such as broken crucible material, known commercially as "pot", and composed principally of clay and graphite. Broken pieces of such absorbent porous refractory material are better for the purpose than balls or other molded or natural pieces. The refractory material C14 on the upper tray C10 is arranged in a circular mass in the central portion of the tray so as to leave an unobstructed annular space surrounding its periphery. The refractory material C16 on the next tray C12 is arranged on the outer portion of the tray so as to leave an unobstructed relatively small central opening. On the remaining trays C13 the layers C17 of refractory material are arranged alternately in the central portion of the tray, and in the outer portion of the tray. It is apparent that the arrangement of the refractory material which has been described provides a series of permeable baffles each 45 of which has an extended surface of absorbent porous material and which leave a free but tortuous flow passage of non-uniform cross-section from the top of the pot to the bottom thereof.

50 On the layer C14 of refractory material on

the upper tray C10 is placed a deflector or spreader C18 formed of a molded mass of refractory material having an upper deflecting surface C19 which is convex and spherically curved. The deflector is best provided with a plurality of small vertical holes C18a for permitting some of the liquid fuel to pass through the deflector to the part of the permeable bed C14 below it.

55 The trays may be spaced uniformly in the body, except that the space C20 between the trays C10 and C12 is desirably larger than the space between the other trays.

The top of the converter is closed by a cover plate C30 which contains a central opening C31 through which air, liquid fuel and steam are introduced into the pot C3. A cylindrical flange C32 extends upwardly around this opening C31 and a higher cylindrical flange C33 extends upwardly outside 85 the flange C32. A cover C34 is secured to the upper end of the outer flange C33. The cover plate C30 and the cover C34 are covered with insulating material C35 which is confined by an outer casing C36.

90 The air pipe 13 communicates with an inlet opening C37 in the flange C33, so that air is drawn into the annular space between the flanges C32 and C33, over the inner flange C32 and down into the pot C3 through the central opening C31 in the cover plate C30. The flow of air into the pot is regulated by a valve C40 at the top of the flange C32. This valve includes a fixed shutter C41 and a movable shutter C42 having a hollow stem C43 100 which extends through central openings in the cover C34 and the casing C36. A handle C44 is fixed on this hollow stem outside the casing C36.

105 Within the flange C32 is placed a Venturi tube C50 through which the air passes in entering the pot C3. The reduction in the pressure of the air at the throat of this Venturi tube, concomitant with the increase in the velocity of the air at this point, is utilized in 110 drawing the liquid fuel into the pot C3 from the float chamber 16. For this purpose the float chamber is connected by a pipe C51 with an annular passage C52 surrounding the throat of the Venturi tube C50 and communicating therewith through transverse holes C53. The holes C53 are located slightly above the liquid level maintained in the float chamber 16 so that no fuel flows into the pot except when there is a subatmospheric pressure 115 in the throat of the Venturi tube.

120 A valve C54 in the pipe C51 provides an adjustable restriction for controlling the amount of liquid fuel drawn into the converter. The amount drawn in depends on the pressure reduction in the Venturi throat and on the adjustment of the valve, and in the operation of the converter the fuel supply varies automatically according to the suc- 125 130

tion applied to the converter, that is, the amount of gas required, as hereinafter described.

The steam, which is supplied through the pipe 28, passes through a needle valve C60 mounted on the upper end of the hollow stem C43. From this valve the steam passes through the hollow stem C43 into a nozzle pipe C61 which extends down through the middle of the Venturi tube C50 and has at its lower end an outlet opening C62 located near the lower end of the Venturi tube and directed toward the center of the deflecting surface C19 of the mass C18. The nozzle pipe C61 is threaded at its upper end and screwed into the lower end of the hollow stem C43, so that it may easily be detached. By substituting for the nozzle pipe C61 a similar nozzle pipe having a different external diameter, the effective area of the throat of the Venturi tube C50 may be varied to adapt the converter for most efficient use in connection with internal combustion engines of different sizes, or to adapt the Venturi tube for use in converters of different capacity within limits.

The fuel gas which is drawn out of the bottom of the pot C3 through the central opening in the refractory material on the lowest tray 30 is directed upwardly by a horizontal partition C65 extending across the converting chamber below the pot. The gas passes up through the cylindrical space between the pot C3, or inner casing, and the outer casing, or wall, C1 and 35 thence into the pipe 10 which communicates with said cylindrical space through the wall C1 near the top thereof.

For convenience in operation, the converter may be provided with a pyrometer C70 having a rod C71 extending into the cylindrical outer casing, or space between the outer wall C1 and the inner casing, or pot, C3, and with a peep hole C72 extending through the casing C36, the insulation C35 and the 45 cover plate C30, and having a glass C73 through which the upper portion of the pot chamber is visible.

During the operation of the converter a high temperature is maintained in the pot C3 by partial combustion of the fuel and other reactions taking place therein. In order to start the operation of the converter it is necessary to heat a portion of it to a temperature above the vaporization temperature of 55 the liquid fuel. The invention comprises means for such initial heating by the supply of heat directly to the interior of the converting chamber. As shown, such means includes a conduit C75 leading to an opening C76 in the wall of the pot C3 between the most widely spaced trays C10 and C12 and extending upward through the cover plate C30 and then horizontally outward. Near its outer end is a slide valve C77. The slide 60 valve C77 is provided with a frame C77a to

prevent it from warping. This frame is wider at the top than at the bottom, and the valve fits in a downwardly tapering slot, or slideway, C77b formed at the outer end of the conduit C75. By this construction, I provide a slide valve which may be operated quickly and which always fits tightly. In the conduit C75 beyond the valve C77 is a wick C78 of refractory material to which liquid fuel is supplied from a cup C79. Fuel may be supplied to this cup through a pipe 33 branching from the fuel pipe 17 and provided with a valve 34. In the outer end of the conduit C75 is a lamp, or small fuel receptacle, C80. The lamp C80 rests on a tray C80a provided with a drain pipe C80b to lead off any oil which may be spilled from the lamp. An upwardly directed chimney C81, forming a continuation of the conduit, is provided above the lamp, and a shutter C82 normally closes a lighting opening adjacent the lamp.

The parts of the converter which have been described are sufficient for its successful operation. In order, however, to render the converter more nearly fool-proof, it is provided with certain features which are of use in case of careless or incorrect operation of it.

If too much air is admitted to the converter, an explosive mixture may be formed in the upper part of the pot, and this mixture, in igniting suddenly, may momentarily raise the pressure in the pot above atmospheric pressure. In order to prevent a back flow of gases, should this occur, check valves C83, C84, C85, are provided in the annular air passage between the flanges C32 and C33, in the conduit C75, and in the oil pipe C51 respectively. The check valve C84 in the conduit C75 is of peculiar construction and constitutes a part of my invention. This check valve comprises two plates C84a, C84b, which extend at a fixed angle to each other. The valve is hinged in the conduit C75 in such manner that the plate C84a normally extends across the conduit, resting against a stop as shown, while the plate C84b is inclined inwardly from the plate C84a. The plate C84a contains an opening C84c through which the flame from the starting lamp C80 may be drawn into the pot. In case of an accidental rise in pressure in the pot, the gas starting to flow out through the conduit C75 swings the valve so as to bring the plate C84b across the conduit and against the stop. The valve is, therefore, closed with great rapidity.

If the converter is operated at too low a temperature, or with the zone of combustion not extending far enough down in it, a liquid residue may flow from the bottom of the pot C3 and collect on the partition C65. To permit the removal of such a residue from the converter, a valve C86 is provided in the partition C65 and a drain pipe C87 provided with a valve C88 is connected to the bottom of the converter. An air inlet C89 controlled by a

valve C90 permits the admission of air to the lower portion of the converter, after the valve C86 has been closed, so that the residue trapped in the lower part of the converter 5 may flow out through the drain pipe C87.

The steam which is supplied to the converter through the pipe 28 has several important functions which are hereinafter explained. In order to perform these functions efficiently, it is desirable that the steam be supplied at a rate which may be nicely regulated and under a uniform pressure. The drawings illustrate a means for supplying steam under a uniform pressure, which 10 forms the subject matter of my Patent No. 1,787,826, dated December 3, 1929. According to the invention claimed in that patent, the supply of steam under uniform pressure is obtained by providing a flash boiler and 15 maintaining the water supplied to the boiler under a pressure equal to the steam pressure desired and admitting the water to the boiler through a passage so constructed that steam and water cannot pass through it in opposite 20 directions.

The water in the tank 24 is maintained under a uniform pressure by pumping air into the top of this tank through a pipe 35. A hand pump 36 may be provided for this purpose. As the tank may be large compared to the amount of water consumed, the hand pump need be operated only occasionally in order to maintain the desired pressure in the tank 24. In passing from the tank 24 to the 25 boiler B through the pipe 25, the water goes through a U-shaped pipe B1 and a constricted passage in a needle valve B2, both inserted in the pipe 25 near the boiler.

In operation, the flash boiler B is maintained heated to a temperature well above the boiling point of water by the heat of the exhaust gases which pass through the casting 23. When the boiler has been heated, the needle valve B2 is opened sufficiently to permit a slow flow of water under the pressure maintained in the tank 24. As soon as any water enters the boiler B through the needle valve B2, this water is converted into steam, creating a pressure in the boiler. If this 30 pressure is equal to or greater than that maintained in the tank 24, it prevents a further flow of water through the needle valve B2. The U-shaped pipe B1 prevents steam from the boiler B from passing back through the pipe 25. When the steam consumption is small, it is possible to omit the U-shaped pipe B1, and to rely on the needle valve B2 to prevent back flow of the steam. The smaller the 35 passage through the needle valve B2, the more completely will it prevent the passage of the steam through it past the water.

When by condensation, or consumption, of the steam formed in the boiler, the pressure in the boiler falls somewhat below that maintained in the tank, additional water enters the

boiler slowly through the needle valve and flashes into steam, again raising the pressure in the boiler. I have found that while the pressure of the steam in the boiler oscillates somewhat, it remains always approximately 70 equal to the pressure maintained in the tank 24. The oscillations of steam pressure are damped out in the expansion chamber 27, so that the steam is supplied under approximately constant pressure to the needle valve 75 C60. As this pressure remains constant, the rate of flow of the steam into the converter remains constant for any given setting of the needle valve C60. The rate may, however, be varied by adjustment of this needle valve, 80 and the boiler will supply the amount of steam required.

The use of the apparatus which has been described is as follows:—

In placing the apparatus in operation, the engine E is first operated in the usual manner by means of volatile fuel, such as gasoline, supplied through a pipe 38 to a carburetor E3 connected with the intake manifold E1 of the engine. Sufficient air to form a proper mixture is admitted by adjustment of the carburetor air valve E4. The starting lamp C80 is lighted, oil is supplied to the wick C78 from the cup C79, and the slide valve C77 is opened, the shutter C82 having first been 95 closed in order to avoid possible harm to the operator if there should be an explosion when the valve C77 is opened. A valve 39 in the gas pipe 10 is then partly opened and the carburetor air valve E4 is closed a little. This causes the suction of the engine to be applied to the pipe 10 so that it draws air from the converter. As a result, the air valve C40 being closed or only partly open, air is 100 drawn into the pot C3 through the chimney C81 and conduit C75. This current of air sucks the flame from the lamp C80 into the conduit and ignites the oil in the wick C78, and the flame from the wick is drawn into the space C20 in the pot C3 between the trays C10 and C12. The air valve C40 is partly 105 opened to admit some air to the converting chamber to burn fuel vapor passing into the converting chamber with the flame from the conduit C75, and as soon as this portion of the pot is well heated, and the valve C54 in the fuel pipe C51 is partly opened. A little steam is then admitted to the pot by opening the needle valve C60 slightly. The liquid fuel 110 drawn in through the Venturi tube C50 is vaporized and ignited by the flame in the space C20 between the two upper beds. When the combustion thus produced has heated the pot sufficiently to maintain combustion without further use of the wick C78, a condition 115 which occurs when the pyrometer C70 indicates about 300° F., the oil supplied to the wick from the cup C44 is cut off, the slide valve C77 is closed, and the lamp C80 is extinguished. More liquid fuel is then admit- 120 125 130 135

ted to the pot by further opening the valve C54 and the air valve C40 is further opened and the temperature of the pot rises with a corresponding rise in the temperature indicated by the pyrometer C70. The valve C54 is gradually opened during this rise in temperature and may be opened sufficiently to supply oil at a rate sufficient for the normal operation of the converter when the temperature indicated on the pyrometer reaches 450° F. The needle valve C60 is opened slightly more during the rise in temperature in the pot, sufficient steam being admitted to prevent combustion from taking place above the upper tray C10. When the pyrometer indicates 800° F. the air valve C40 is closed somewhat and set so as to permit only sufficient combustion to maintain the desired indication by the pyrometer of the temperature of the outflowing gases in the space between the inner and outer casings of the converter. It has been found best to maintain this temperature at about 800° F. but the most desirable temperature to be maintained will vary with conditions and according to the design of the converter, and may vary within quite wide limits for a given converter.

As the pot is heating up, the valve 39 is opened more and more. When the pot has been heated up to the temperature required for full operation, or before this time, if the operation of the engine indicates that a combustible gas is being drawn into the intake manifold from the pipe 10, the supply of gasoline to the carburetor E2 may be shut off by closing a valve 41 in the pipe 38, and the valves 39 and E4 are adjusted so that sufficient air is drawn in through the valve E4 to form an explosive mixture with the gas drawn into the intake manifold from the pipe 10.

The fuel gas passing from the converter has a large content of methane and illuminants, giving it a high B. t. u. value, and also a smaller content of uncombined hydrogen and uncombined oxygen. The gas is a clean gas requiring no scrubbing before use in the engine.

While I do not wish to limit myself to any theory as to the operation of the converter in producing this gas, I will state tentatively the nature of the operation which I believe takes place within the converter so that my invention may be understood as clearly as possible.

The liquid fuel which is drawn into the pot through the Venturi tube drips upon the distributor C18 and is spread out by the distributor so that it permeates evenly into the upper bed C14 and spreads over its extended surface, some of the liquid being absorbed in the refractory material of the bed. Part of the liquid fuel is vaporized in the bed C14, while a considerable portion of the liquid drips down from the bed C14, and unvaporized portions

of the fuel liquid thus pass downward from bed to bed, spreading over the extended surface of successive beds and being absorbed to some extent in the refractory material of the beds. The fuel vapor flows downward through the tortuous passage with the air and steam, and combustion takes place below the tray C10 and, most desirably below the space C20. The heat of this combustion vaporizes the liquid fuel spread over and absorbed in the refractory material of the beds. Although the air supplied is sufficient for complete oxidization of only a part of the carbon contained in the fuel, the partial combustion raises the lower part of the pot to flame temperature. The temperature is such that the fuel is "cracked", that is, the heavy hydrocarbons in it are split up into lighter hydrocarbons. At the same time the steam is decomposed into oxygen and hydrogen. Both these elements combine with carbon from the fuel.

The fact that these operations take place in a tortuous passage formed in the pot by the beds C16 and C17 of refractory material has several important advantages. In particular, and aside from the effect of the beds on the vaporization and gasification of the fuel, the zig-zag flow thus produced causes a thorough mixing of the fuel, air and steam and of the gaseous products of the reactions which take place. Such mixing is greatly increased by the fact that the passage is of non-uniform cross-section, so that the gaseous stream is continually either speeding up or slowing down as it passes through different parts of the converter. The speed of the stream is greatest when it passes through the central openings in the masses which provide central openings. The rapid flow of the stream through each central opening tends to throw away drops or minute particles of liquid fuel which are carried along in the stream downwardly against the mass of refractory material below the opening, so that such liquid fuel is held in one of the beds until it is vaporized. This prevents any liquid fuel from being carried over into the engine.

The steam which is introduced into the pot has several important functions:

In dissociating, it furnishes nascent oxygen and hydrogen which combine with free carbon present in the pot, including any soot which might otherwise be deposited in the refractory material on the trays in starting the operation of the pot. The steam is supplied in amount sufficient not only to insure oxidation of all free carbon formed in the pot, but also to leave some free oxygen in the gas which is withdrawn from the pot. It, therefore, effectively prevents deposition of carbon within the pot.

The steam prevents combustion in the upper part of the pot, and especially in the

space above the upper bed C14. This I believe to be due, principally at least, to the fact that the steam dilutes the mixture of fuel vapor and air so as to prevent the formation of an inflammable mixture at and near the top of the pot. The extent to which the zone of combustion is depressed depends upon the relative amount of steam introduced. I have found it desirable to introduce such a relative amount of steam that combustion does not take place for some distance below the upper bed. In a converter such as shown, supplying gas to an internal combustion engine developing approximately 40 horsepower, the best results have been obtained when an amount of steam produced by the evaporation of from 1 to 1½ gallons of water per hour is supplied to the converter while gas oil is being supplied at the rate of about 3 gallons per hour. I believe also that the prevention of combustion in the space above the upper bed in the construction shown is due in part to the fact that the steam introduced as a jet into the pot and striking the deflector at a high velocity spreads in a layer over the surface of the deflector and of the upper bed C14 and tends to prevent the air from mixing with the fuel vapor formed at the deflector and bed C14. The fact that no combustion occurs in the upper part of the pot is of advantage in that it affords a better opportunity for complete vaporization and gasification of the fuel by preventing the oxygen of the air from being used up by combustion in the upper part of the pot and combustion thus limited to an upper zone through which a considerable portion of the liquid fuel would pass without being vaporized, so that, even if such portion of the fuel were vaporized in a lower part of the pot, the vapor would not be subjected to the intense gasifying heat of the combustion zone and a considerable part of the fuel would reach the bottom of the pot in liquid form or as unfixed or condensable vapor. The depression of the combustion zone also prevents sudden ignitions of fuel vapor in the upper part of the pot, which would cause undesirable fluctuations of pressure in the upper part of the pot affecting the supply of liquid fuel and air.

The steam also serves to extend the zone of combustion within the pot, and this is of great advantage in securing more complete cracking of the fuel and increasing the gas producing capacity of the pot. By admitting sufficient steam, the combustion may be made to begin at any desired distance below the upper bed C14, and the zone of combustion may be made to extend well down toward or to the bottom of the pot.

Because of the vaporization of the liquid fuel in the upper porous and permeable beds and the prevention of combustion in the upper part of the converting chamber, the

upper beds are maintained at a comparatively low temperature and trouble from the formation of carbon is thus avoided.

The maintenance of sub-atmospheric pressure in the pot has important advantages. It makes it possible to draw in the air and the fuel by a suction which varies with the rate at which the gas is used, so that the rate of supply both of the air and of the liquid fuel varies automatically with changes in the rate at which the gas is used. Furthermore, since the supply of fuel depends on the maintenance of a sub-atmospheric pressure in the pot, the rate at which the fuel is supplied even in full capacity operation of the converter is automatically regulated. This is because, if an excess of liquid fuel is drawn into the pot, the rapid vaporization of this fuel decreases the degree of sub-atmospheric pressure in the pot and in consequence checks the supply of liquid fuel to the pot.

What is claimed is:—

1. Apparatus for producing fixed fuel gas, comprising a means providing a converting chamber having an air inlet at the top thereof, means for applying suction to the bottom of the chamber to draw the gas from the chamber and to maintain a sub-atmospheric pressure therein, means for supplying liquid fuel to be drawn into the top of said chamber with air in proportions such that the air will be sufficient for burning only a small part of the fuel, a plurality of spaced superposed permeable baffles arranged in said chamber to leave a free tortuous passage extending from the top of the chamber generally downward past and between the baffles, and means for introducing steam into the top of the chamber in quantity sufficient to prevent combustion in said passage near the entrance end thereof and to extend the zone of combustion.

2. Apparatus for the continuous production of fixed fuel gas, comprising means forming a converting chamber having means for admitting liquid fuel at its top and for admitting air in quantity sufficient for combustion of a small part of the fuel, and having a gas outlet at its bottom; and a plurality of permeable baffles of refractory material positioned in spaced superposed relation in said chamber so that liquid fuel may drip through the upper baffle and downward from baffle to baffle, said baffles being arranged to leave a free tortuous passage extending generally downward through the converting chamber past and between the baffles.

3. Apparatus for the continuous production of fixed fuel gas, comprising means forming a converting chamber having means for admitting liquid fuel at its top and for admitting air at its top in quantity sufficient for combustion of a small part of the fuel, and having a gas outlet at its bottom; a plurality of permeable baffles of refractory material

positioned in spaced superposed relation in said converting chamber so that liquid fuel may drip through the upper baffle and downward from baffle to baffle, said baffles being arranged to leave a free passage extending downward through the converting chamber; means for applying suction to the gas outlet to draw gas from the converting chamber and to maintain a sub-atmospheric pressure therein; and means for supplying steam to the top of the converting chamber in quantity sufficient to prevent combustion near the top of the chamber and to extend the zone of combustion within the chamber.

4. Apparatus for the continuous production of fixed fuel gas, comprising means forming a converting chamber having a vaporizing portion and a gasifying portion, and having a gas outlet from the gasifying portion, a plurality of absorbent masses of refractory material arranged in the vaporizing portion of the chamber so as to leave a free tortuous passage therein extending past said absorbent masses and to the gasifying portion of the chamber, means for introducing liquid fuel into the chamber for distribution on said absorbent masses, means for admitting air to the chamber in quantity sufficient for burning only a small part of the fuel vapor, means for applying suction to the gas outlet for withdrawing gas from the chamber and for causing the air and fuel vapor to flow through the chamber, and means for supplying steam to the chamber in quantity sufficient to prevent combustion in the vaporizing portion of the chamber and to be decomposed and cause the consumption of free carbon in the gasifying portion of the chamber.

5. Apparatus for the continuous production of fixed fuel gas, comprising means forming a converting chamber having an air inlet opening and a gas outlet opening, a plurality of baffles of absorbent refractory material arranged in the chamber so as to leave a free tortuous passage from the air inlet opening to the gas outlet opening, means for introducing liquid fuel into the chamber for distribution on the baffles near the inlet end of the chamber, means for maintaining a flow producing pressure difference between the inlet opening and the outlet opening, means for limiting the amount of air admitted to the chamber, and means for supplying steam at the inlet end of the chamber in quantity sufficient to prevent combustion at and near the inlet end of the chamber.

6. Apparatus for the continuous production of fixed fuel gas, comprising means forming a vertically elongated converting chamber having a gas outlet at the bottom thereof, a plurality of spaced superposed permeable baffles of absorbent refractory material arranged in said chamber to leave a free tortuous passage of non-uniform cross-

section extending from the top of said chamber generally downward past and between the baffles, means for supplying liquid fuel to said chamber and distributing it on the uppermost baffle, means for supplying air at the top of said chamber in quantity sufficient for combustion of only a small part of the fuel vapor, and means for supplying steam at the top of said chamber in quantity sufficient to depress and extend the zone of combustion within the chamber, whereby combustion will be caused to take place and a gasifying temperature maintained in a portion of said passage below the upper portion thereof, and a lower temperature will be maintained in the upper portion of the chamber.

7. Apparatus for the continuous production of fixed fuel gas, comprising means forming a converting chamber having an air inlet opening at the top and a gas outlet opening at the bottom, a plurality of spaced superposed permeable baffles arranged in said chamber to leave a free tortuous passage extending from the top of said chamber generally downward past and between the baffles including an opening in one of the baffles located opposite an imperforate portion of the succeeding baffle, such opening having a cross-sectional area less than the average cross-sectional area of the passage, means for supplying liquid fuel to said chamber and distributing it on the uppermost baffle, and means for supplying steam to the top of said chamber.

8. Apparatus for the continuous production of fixed fuel gas, comprising a casing forming a converting chamber having an air inlet opening at the top and a gas outlet opening at the bottom, a plurality of spaced superposed permeable baffles arranged in said chamber to leave a free tortuous passage extending from the top of said chamber generally downward past and between the baffles, alternate baffles having their peripheries spaced inwardly from the walls of the chamber and the other alternate baffles containing central openings whose cross-sectional areas are less than the cross-sectional area of other parts of the passage, and means for supplying liquid fuel to said chamber and distributing it on the uppermost baffle, and means for supplying steam to the top of said chamber.

9. Apparatus for the continuous production of fixed fuel gas, comprising means providing a vertically elongated converting chamber having a gas outlet at the bottom thereof, a plurality of spaced superposed permeable beds of refractory material arranged within the chamber so as to leave a free tortuous passage extending generally downward past and between the beds, means for supplying liquid fuel to said chamber and distributing it on the upper bed, and

means for supplying to the top of said chamber above the upper bed air in quantity sufficient for combustion of a small part of the fuel and steam in quantities sufficient to depress and extend the zone of combustion.

- 5 10. Apparatus for the continuous production of fixed fuel gas, comprising means providing a vertically elongated converting chamber having a gas outlet at the bottom thereof, a plurality of spaced superposed permeable beds of absorbent refractory material arranged within the chamber so as to leave a free tortuous passage extending generally downward past and between the beds, means 15 for supplying liquid fuel to said chamber and distributing it on the upper bed, and means for supplying to the top of said chamber above the upper bed air in quantity sufficient for combustion of a small part of the fuel and steam in quantity sufficient to depress and extend the zone of combustion.

9825 9830 9835 9840 9845 9850 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999

and a steam nozzle entering the upper end of the chamber and directed toward the top of the upper bed.

14. Apparatus for the continuous production of fixed fuel gas, comprising means providing a converting chamber having a gas outlet at the bottom thereof, means for applying suction to the gas outlet, a plurality of spaced superposed permeable beds of refractory material arranged within the chamber so as to leave a free tortuous passage extending generally downward past and between the beds, means providing an air inlet opening in the top wall of the chamber having the form of a Venturi tube having its discharge end directed toward the upper bed, a liquid fuel supply conduit communicating with said Venturi tube at its throat, and a steam nozzle pipe extending axially through said Venturi tube for supplying steam directed toward the upper bed.

15. Apparatus for the continuous production of fixed fuel gas, comprising means providing a converting chamber having a gas outlet, a plurality of spaced superposed permeable beds of refractory material set horizontally within the chamber near the top thereof and spaced from the side walls thereof, means providing an air inlet opening in the top of the chamber having the form of a Venturi tube having its discharge end directed toward the upper surface of said bed, a liquid fuel supply conduit communicating with said Venturi tube at its throat, a steam conduit, and a steam nozzle detachably secured at the end of said steam conduit and extending axially through the throat of the Venturi tube for supplying steam to the chamber.

16. Apparatus for the continuous production of fixed fuel gas, comprising means providing a converting chamber having a gas outlet, a plurality of spaced superposed permeable baffles of refractory material arranged within the chamber so as to leave a free tortuous passage extending generally downward past and between the baffles, means providing an air inlet opening in the top wall of the chamber having the form of a Venturi tube having its discharge end directed toward the upper baffle, a liquid fuel supply conduit communicating with said Venturi tube at its throat, a distributor arranged to distribute over the upper baffle liquid fuel introduced into the chamber through the Venturi tube, and means for supplying steam to the top of said chamber.

17. Apparatus for the continuous production of fixed fuel gas, comprising means providing a converting chamber having a gas outlet, a permeable baffle of refractory material set horizontally within the chamber near the top thereof and spaced from the side walls thereof, a distributor on said baffle having a convex upper surface, means providing

- ing an air inlet opening in the top wall of the chamber having the form of a Venturi tube having its discharge end directed toward the upper surface of said distributor, 5 a liquid fuel supply conduit communicating with said Venturi tube at its throat, and a steam nozzle pipe extending axially through the Venturi tube and directed toward the upper surface of said distributor.
- 10 18. Apparatus for the continuous production of fixed fuel gas, comprising a casing forming a chamber having an inlet for liquid fuel and air at its top and a gas outlet at its bottom, a plurality of spaced superposed forami- 15 nous horizontal supports in said chamber, a permeable bed of small pieces of refractory material on the central portion of each alternate support leaving the peripheral portion of the support unobstructed, and a permeable 20 bed of small pieces of refractory material on the peripheral portion of each of the other alternate supports leaving a central portion of the support unobstructed.
19. Apparatus for the continuous production 25 of fixed fuel gas, comprising an inner casing, an outer casing surrounding the inner casing, refractory material in the space within the inner casing, means for introducing liquid fuel and air into the space within the inner casing and causing a partial combustion of the fuel therein, and means for circulating the hot fuel gas formed in the inner casing in the space between the inner and outer casings so as to check dissipation 35 of heat from the inner casing.
20. Apparatus for the continuous production 40 of fixed fuel gas, comprising an inner casing forming a converting chamber, an outer casing surrounding the inner casing, a plurality of permeable baffles of refractory material arranged within said chamber so as to leave a free tortuous passage extending generally downward past and between the baffles, means for admitting liquid fuel and 45 air to the top of said chamber, the bottom wall of said chamber having an opening to the bottom portion of the space between the inner and outer casings, fuel gas outlet from the top of said space, and means for applying suction to said outlet, whereby a draft will be created downward through said chamber and the hot fuel gas formed in said chamber will be drawn upward through the space between the inner and outer casings so as to 55 check dissipation of heat from the inner casing and to heat the upper portion of the inner casing.
21. Apparatus for the continuous production 60 of fixed fuel gas, comprising means providing a converting chamber having a gas outlet, a plurality of permeable baffles of refractory material arranged within the chamber in superposed relation and so as to leave a free passage from the top of the chamber 65 downward including an enlarged space be-
- tween baffles in the upper part of the chamber, means for introducing liquid fuel and air into the top of said chamber for partial combustion of the fuel in the chamber, and preliminary heating means comprising a 70 source of combustion outside said chamber and means for introducing flame from said source of combustion into said enlarged space.
22. Apparatus for the continuous production 75 of fixed fuel gas, comprising means providing a converting chamber having a gas outlet, a plurality of permeable baffles of refractory material arranged within the said chamber so as to leave a free tortuous passage 80 extending generally downward past and between the baffles, means for applying suction to the gas outlet for drawing gas from the chamber and maintaining a sub-atmospheric pressure therein, means for admitting liquid 85 fuel and air to the top of the chamber in proportions for partial combustion of the fuel in the chamber, and preliminary heating and igniting means comprising a source of combustion outside the chamber and a conduit 90 leading from said source of combustion into an intermediate part of said passage.
23. Apparatus for the continuous production 95 of fixed fuel gas, comprising means providing a converting chamber having an unobstructed tortuous passage extending therethrough, means for applying suction to the outlet end of the passage to draw gas therefrom and to maintain a sub-atmospheric pressure 100 therein, means for admitting liquid fuel and air to the entrance end of said passage in proportions for partial combustion of the fuel, and preliminary heating and igniting means comprising a conduit communicating with said passage, an absorbent wick in said 105 conduit, and means for supplying fuel to said wick.
24. Apparatus for the continuous production 110 of fixed fuel gas, comprising means providing a converting chamber, means for introducing liquid fuel and air into said chamber in proportions for partial combustion of the fuel, means for applying suction to the chamber to draw gas therefrom and to maintain a sub-atmospheric pressure therein, and preliminary heating means comprising a conduit opening into said chamber, an absorbent wick in said conduit, means for supplying liquid fuel to said wick, a valve for closing the conduit outside said wick, an igniting 115 lamp in the conduit outside said valve, the conduit having a lighting opening adjacent said lamp, a shutter normally closing said lighting opening, and a chimney directed upward from said lamp and forming a continuation of the conduit.
25. Apparatus for the continuous production 120 of fixed fuel gas, comprising means providing a converting chamber, means for introducing liquid fuel and air into said chamber 125

ber in proportions for partial combustion of the fuel, means for applying suction to the chamber to draw gas therefrom and to maintain a sub-atmospheric pressure therein, and preliminary heating and igniting means comprising a conduit opening into said chamber, means for supplying fuel to burn in said conduit, and a check valve in said conduit comprising two plates extending at an angle to each other, one of said plates containing an opening and said valve being hinged so that the plate containing the opening normally extends across the conduit and the other plate is normally inclined inwardly in the conduit.

15 26. Apparatus for the continuous production of fixed fuel gas, comprising means providing a converting chamber, means for introducing liquid fuel and air into said chamber in proportions for partial combustion of the fuel, means for applying suction to the chamber to draw gas therefrom and to maintain a sub-atmospheric pressure therein, and preliminary heating and igniting means comprising a conduit opening into said chamber, 20 means for supplying fuel to burn in said conduit, and means for closing said conduit comprising a tapered slideway and a slide valve having a frame whose upper portion is wider than its lower portion to fit said tapered slideway.

30 In testimony whereof, I have hereunto set my hand.

PHILIP MASON CABELL.

CERTIFICATE OF CORRECTION.

Patent No. 1,834,087.

Granted December 1, 1931, to

PHILIP MASON CABELL.

It is hereby certified that error appears in the printed specification of the above numbered patent requiring correction as follows: Page 4, line 116, strike out the word "and"; page 9, line 48, claim 20, before the word "fuel" insert the article a; and that the said Letters Patent should be read with these corrections therein that the same may conform to the record of the case in the Patent Office.

Signed and sealed this 9th day of February, A. D. 1932.

(Seal)

**M. J. Moore,
Acting Commissioner of Patents.**
